UNITED STATES PATENT OFFICE.

BENJAMIN F. CUMMINGS, OF DRYDEN, OKLAHOMA.

WHIFFLETREE.

1,076,352.

Specification of Letters Patent.

Patented Oct. 21, 1913.

Application filed February 26, 1913. Serial No. 750,924.

To all whom it may concern:

Be it known that I, BENJAMIN F. CUMMINGS, a citizen of the United States, residing at Dryden, in the county of Harmon 5 and State of Oklahoma, have invented certain new and useful Improvements in Whiffletrees, of which the following is a specification, reference being had to the accompanying drawings.

10 This invention relates to improvements in whiffletrees, and an object thereof is the provision of a whiffletree which is provided with adjustable means whereby the weight of the load may be equally distributed to horses 15 of different weight or pulling power.

Another object of this invention is the provision of a whiffletree which is provided with a truss rod, the traces of the harness being secured to the opposite ends of the 20 truss rod so that the strain will be distributed the entire length of the whiffletree.

Still another object of this invention is the provision of the whiffletree comprising a draft bar, the bar having a central bridge 25 secured thereto and caps mounted on its opposite end, each of the caps being formed of a stationary member and an outwardly movable member, a truss rod having its intermediate portion engaged with said bridge, 30 and its opposite ends connected to the movable members of the caps, whereby the shock usually imposed centrally upon the draft bar will be distributed longitudinally thereof.

35 A still further object of this invention is the provision of a whiffletree comprising a draft bar, the bar having a central bridge secured thereto and caps mounted on its opposite ends, and a truss rod having its intermediate portion engaged with said bridge, the caps being formed of a stationary member and a movable member, the opposite 40 ends of the truss rod being connected to the movable members of the caps and the traces 45 of the harness being also connected to the movable members of the caps, whereby the strain ordinarily imposed upon the central portion of the draft bar will be equally distributed throughout its entire length.

50 With these and other objects in view, the invention consists in certain novel constructions and arrangement of parts, to be hereinafter more fully described, claimed and illustrated in the accompanying drawings, in 55 which—

Figure 1 is an elevation of my device used

as a four horse evener. Fig. 2 is a top plan view of one end of the draft bar. Fig. 3 is a top plan view of my device used as a doubletree. Fig. 4 is an edge view of the bridge piece or spacing truss rod from the bar. Fig. 5 is an elevation of the central sleeve. Fig. 6 is a longitudinal section of the central sleeve. Fig. 7 is an edge view of the stationary section of the cap. Fig. 8 is a side view partly in section thereof. Fig. 9 is an end view thereof. Fig. 10 is a top plan view partly in section showing the sections of the cap connected. Fig. 11 is an end view of the movable section of the cap.

Referring more particularly to the drawings, the numeral 1 designates the draft bar of the equalizer, and 2 a sleeve which is slidably mounted on said bar and which is held in an adjusted position by a set screw 70 3. The sleeve is formed with a reduced hollow extension 4 in the end of which is a swivelly mounted hook 5, which is adapted for engagement with a portion of the running gear of a wagon. The opposite end of 75 the sleeve is formed with a rib 6 which is provided with an opening 7 whereby a clevis pin 8 may be passed through the opening to secure the draft bar to the vehicle. Secured in the reduced portion of the sleeve is a 80 bridge member 9 which is adapted to support the intermediate portion of the truss rod 10 in spaced relation with the bar, the opposite ends of the truss rod being adapted for engagement with the caps 11 which are 85 mounted on the reduced ends 12 of the bar 1.

Each of the caps 11 is formed of a stationary section 13, and a movable section 14, the stationary section being formed on one end with a socket 15 for engagement with the reduced end 12 of the bar. The opposite end of the stationary section is formed with a pair of spaced ribs 16, the upper ends of which are enlarged to form longitudinally extending curved locking tongues 17 which are 90 adapted for engagement in spaced arcuate recesses 18 formed in the opposed end of the movable section 14 of the cap. The wall 19 which spaces the recesses 18 of the movable member is adapted to engage in the recess 95 100 formed by the ribs 16 in the stationary member thereby preventing relative lateral movement of the sections of the cap. The curved end walls 21 of the recesses 18 are 105 enlarged and cam-shaped, as at 22, at one end, the cam-shaped portions of the walls resting against the ribs 16 under the tongue 110

17 of the stationary members, whereby the movable sections are adapted for outward movement with relation to the stationary sections of the caps. The movable section 5 of each cap is formed with an outwardly facing hook 23 in which the looped ends 24 of the truss rod 10 are adapted to engage, the truss rod being adapted to maintain the movable sections of the caps in their inner 10 positions. Each of the movable sections 14 is provided at its forward end with an opening 25 in which a hook 26 is loosely mounted, the hooks being adapted for engagement with the traces of the harness when the device 15 is used as a swingletree or doubletree. In the drawings I illustrate a four horse whiffletree, and in this construction the hooks 26 are connected to the hooks 5 of the sleeves 2 of the doubletrees 27, the caps on 20 the opposite end of the doubletree 27 being connected to the central sleeve of the swingletrees 28. It will be seen in the drawings, that the swingletrees 28 are connected to the doubletrees 27 by caps and sleeves of the 25 same construction as those shown connected to the bar 1, and if desired the doubletrees 27 and the swingletrees 28 may be removed from the bar 1, so that the device may be used as a one horse or a two horse whiffletree. If the device is used as a four horse 30 evener, and one of the horses attached to the swingletrees 28 of the doubletrees 27 is stronger than the other horse attached to the doubletree, it will be only necessary to 35 loosen the set screw 3 in its opening in the sleeve so that the sleeve may be adjusted the direction desired to give the weaker horse greater leverage than the stronger horse, and thereby equalize the load.

40 Having thus described my invention, what I desire to claim and secure by Letters Patent is:

1. A device of the character described comprising a bar, caps consisting of a stationary section and a relatively movable section mounted upon the ends of said bar, said stationary section of each cap being formed with spaced locking tongues and the movable section of each cap being formed with 45 recesses for the reception of said tongues, and a truss rod having its opposite ends connected to the movable sections of said caps, as and for the purpose described.

2. A whiffletree comprising a bar, a sleeve

slidably mounted on said bar, said sleeve 55 having a reduced hollow extension, a bridge piece mounted upon said bar within said extension, caps mounted upon the opposite ends of said bar, said caps comprising a stationary section and a relatively movable section, and a truss rod having its opposite ends connected to the movable sections of the caps, the intermediate portion of said truss rod bearing against the outer face of said bridge piece within the reduced hollow extension of said sleeve, as and for the purpose described.

3. A device of the character described comprising a bar, a sleeve slidably mounted on said bar, said sleeve having a reduced 70 hollow extension, a bridge piece connected to said extension, caps mounted upon the opposite ends of said bar, and a truss rod having its opposite ends connected to said caps and its intermediate portion bearing 75 against said bridge, whereby said truss rod is maintained in spaced relation with said bar, as and for the purpose described.

4. A whiffletree comprising a bar, a sleeve 80 slidably mounted on said bar, a bridge piece connected to said sleeve, the opposite ends of said bar being formed with reduced extensions, sectional caps mounted on said reduced extensions, one section of each of said caps being formed with a hook, and a truss 85 rod having its opposite ends connected to said hooks, and its intermediate portion engaged with said bridge piece, as and for the purpose described.

5. A device of the character described 90 comprising a bar, caps comprising a stationary section and a movable section mounted upon the ends of said bar, said stationary section of each cap being formed with spaced locking tongues and the movable section of each cap being formed with recesses 95 for the reception of said tongues, hooks formed on said movable sections, a truss rod having its opposite ends connected to said hooks, and means for spacing said truss rod 100 from said bar, as and for the purpose described.

In testimony whereof I hereunto affix my signature in the presence of two witnesses.

BENJAMIN F. CUMMINGS.
